R. G. CRAWFORD

FROG FOR RAILWAYS

Filed Aug. 30, 1923

Inventor:

UNITED STATES PATENT OFFICE.

ROBERT G. CRAWFORD, OF PITTSBURGH, PENNSYLVANIA, ASSIGNOR TO THE AMERICAN FROG & SWITCH COMPANY, OF HAMILTON, OHIO, A CORPORATION OF OHIO.

FROG FOR RAILWAYS.

Application filed August 30, 1923. Serial No. 660,217.

To all whom it may concern:

Be it known that I, ROBERT G. CRAWFORD, a citizen of the United States, residing at Pittsburgh, in the county of Allegheny and 5 State of Pennsylvania, have invented certain new and useful Improvements in Frogs for Railways, of which the following is a specification.

It is the object of my invention to provide 10 a simple and effective frog provided with slots or recesses into which the ends of the rails may be inserted for providing support in the frog at both sides of the respective ends of the rails; further, to provide a novel 15 frog into which the ends of the rails may be inserted and held without the necessity of bolting or clamping the ends of the rails to the frog; and, further, to provide a frog with an easer-extension and a fish-extension 20 between which the end of the rail is received for holding the end of the rail in place.

The invention will be further readily understood from the following description and claims, and from the drawing, in which latter:

Fig. 1 is a plan view of my improved device, showing rails extending from the frog, and the rails and cross-ties partly broken away.

Fig. 2 is a side elevation of the same, taken in the direction of the arrow 2 of Fig. 1.

Fig. 3 is a side elevation of the same, taken in the direction of the arrow 3 of Fig. 1.

Fig. 4 is a cross-section of the same, taken on the line 4—4 of Fig. 1, partly broken away.

Fig. 5 is a cross-section of the same, taken 40 on the line 5—5 of Fig. 1, partly broken away, and showing a wheel in dotted lines partly broken away.

Fig. 6 is a plan view of my improved device in association with the ends of rails, the 45 rails having their heads removed and being shown in horizontal section on the line 6—6 of Fig. 2.

Fig. 7 is a cross-section of my improved device, taken on a line corresponding to the 50 line 7—7 of Fig. 2, showing a modification in that there is a bolt passing through the rail-end; and,

Fig. 8 is a perspective view of a detail of my improved device, partly in section on a

line corresponding to the line 8—8 of Fig. 1, 55 but showing a modification in that there is a bolt passing through the rail-ends.

The frog-tongue 11 comprises the point 12. Easer-extensions 13, 14, extend from the heel 15 of the tongue in angular relation, the angle being determined by the angle of the frog, that is, the relative directions in which the rails extend at the frog.

Wings 18, 19, are connected with the tongue by the base 20 of the frog, and are 65 in spaced relation from said tongue by the channels 21, 22. The outer ends of the channels are formed as mouths 23, 24, by the diverging ends 25, 26, of the respective wings.

The easer-extensions 13, 14, at the heel of 70 the frog are connected by the web 30 of the base of the frog, and are respectively provided with tongues 31, 32, which extend lengthwise of the extensions. These tongues are received in the side channels 33, 34, of 75 the rails 35, 36.

The heel of the frog is provided with fish-extensions 38, 39, shown parallel with the respective easer-extensions 13, 14, being respectively laterally braced by the webs 41, 80 42, which form the bottoms of the mouths 23, 24, of the channels 21, 22. These latter extensions are shown provided with tongues 43, 44, which are received in the side channels 45, 46, of the rails 35, 36. 85

The easer-extension 13 and its mating fish-extension 38 form a slot 48 between them, this slot being preferably of a form to correspond to the walls of the side channels at the end of the rail, so that the rail may 90 be slipped endwise into the slot and be supported at both sides by these extensions. The easer-extension 14 and the fish-extension 39 have a similar slot 49 between them, being correspondingly shaped for receiving the 95 end of the rail endwise into said slot and supporting the rail between said extensions.

The web 51 of the base of the frog, which has the channel 52 thereabove, in advance of the throat 53 of the frog, is provided at its 100 respective sides with fish-extensions 55, 56, the relative angles of which correspond with the angle of the frog. These fish-extensions are provided with tongues 57, 58, extending parallel with said extensions and respectively received in the side channels 59, 60, of 105 the rails 61, 62.

Easer-extensions 65, 66, extend parallel

with the fish-extensions 55, 56. They have tongues 67, 68, which are received in the side channels 69, 70, of the rails 61, 62.

Slots 71, 72, are provided between these 5 respective easer-extensions and fish-extensions at the respective sides of the frog. The ends of the rails 61, 62, are arranged to be slipped into the slots 71, 72, and to be supported laterally respectively by the 10 easer-extension and the fish-extension at the side of the frog.

The inner formations of the easer-extensions and fish-extensions and their tongues are such, preferably, as to follow the contour 15 of the sides of the rails, for filling in the side channels of the rails, so that the webs 73 of the rails have lateral support against the tongues, the lower edges of said extensions being provided with rabbets 74, 20 the upper walls of which are preferably slanting to conform to the upper slanting face of the base 75 of the rail, for finding support on said base. The upper edges of said tongues are preferably so formed as 25 to contact the lower slopes of the head 76 of the rail for supporting said head.

When now the ends of the rails are slipped into the slots at the ends of the frog, the 30 said ends of the rails are supported laterally by said extensions, and no further fastening means is necessary between the frog and the rail-ends, although it is desirable that the rails adjacent their ends be suitably secured to cross-ties 78 as by means of spikes 79. 35 Spikes 80 may also hold the frog to cross-ties shown at 81.

The sloping faces 83 of the easer-extensions permit the outer edges of the treads of the wheels of the traveling vehicle to rise 40 upon the frog to prevent endwise jolting of the frog, it being understood that the wheels 84 of railway vehicles usually become worn adjacent their flanges 85, exemplified in dotted lines in Fig. 5, forming annular grooves 45 in the wheels adjacent the flanges, and leaving the outer ends 87 of the treads of the wheels of greater diameter than the diameter of the wheels at said grooves.

The usual lengths of rails are provided 50 with a pair of holes at their ends which are spaced standard distances apart and from the end of the rail. If desired, the respective easer-extensions and fish-extensions at the throat end of the rail may be provided 55 with holes 91, 92, and a bolt 93 passed through these holes and the end hole 94 in the rail, as shown in Fig. 7, with the usual nut 95 and lock washer 96, for connecting the end of the rail with said extensions, the 60 bolt passing through the end one of the holes in the end of the rail. A similar bolt may pass through the second hole 97 at the end of the rail and a corresponding hole in the fish-extension, and be clamped in place 65 by a usual nut and washer.

If desired, the heel end of the frog may also have the ends of the rails bolted thereto, as by means of a bolt 101 shown in Fig. 8, which passes through holes 102, 103, in the respective easer-extensions and fish-extensions at the heel of the frog and the end holes 94 in the end of the rails, as shown in Fig. 8, a nut 105 and washer 106 clamping the parts together. Short bolts may be received through the usual second holes 97 75 at the ends of the rails and mating holes in the easer-extensions 13, 14, usual nuts and washers clamping the parts together. These bolts and nuts may, however, be dispensed with, as sufficient lateral support and connection with the rails is provided by the respective mating easer-extensions and fish-extensions. 80

My improved construction permits an extended easing at each end of the frog over 85 a substantial distance lengthwise of the frog and provides a fish-extension opposite each easer-extension. In the form shown, the fish-extensions are longer than the easer-extensions at one end of the frog and the 90 easer-extensions are longer than the fish-extensions at the other end of the frog, as shown in Fig. 6.

The frog with its extensions is preferably made of a single casting, for instance 95 of a special grade steel.

My invention is especially useful in such relations where temporary tracks are laid, in which the necessity for bolting the ends of the rails to the frog is obviated with my improvement, and it is also especially adapted for use in economically constructing turn-outs in the rail systems of mines for branch tracks into rooms in which mining operations are taking place, and which turn-outs are in practice used only as long as it may take to remove the coal from the room, whereupon change is made in the trackage and the turn-outs and branch tracks taken up and used at a different location. 100

My improved device forms ready and economical and safe means whereby such changing relations may be economically satisfied, as no fitting between the rail-ends and the frog is necessary, and no bolting or other clamping between said rail-ends and the frog is required in my improved device. 115

My improved device also provides ready and economical means whereby turn-outs having short radii may be constructed. 120

Having thus fully described my invention, what I claim as new, and desire to secure by Letters Patent, is:

1. A frog having an easer-extension at one side of a rail-slot and a fish-extension at the other side of said rail-slot to form said rail-slot, said rail-slot arranged to receive the end of a rail. 125

2. A frog having an easer-extension at one side of a rail-slot and a fish-extension 130

at the other side of said rail-slot to form said rail-slot, said rail-slot having side walls provided with tongues and arranged to end-wise receive the end of a rail having side channels, with said tongues located in the side channels of the rail.

3. A frog having an easer-extension at one side of a rail-slot and a fish-extension at the other side of said rail-slot to form 10 said rail-slot, a frog-tongue at the inner end of said rail-slot, a wing spaced from said frog-tongue to form a channel having a widened mouth, and a web at the bottom of said mouth, said web connecting with said 15 wing and having connection with said fish-extension in rear of the inner end of said rail-slot.

4. A frog provided with end-slots at each 20 end of the frog for the endwise insertion of track-rails at the respective ends of the frog, each of said end-slots having a wall at each side thereof to laterally support the end of the track-rail inserted therein, and the walls of each of said slots being of un- 25 equal lengths.

5. A frog having easer-extensions and fish-extensions at each end of the frog, spaced apart to form slots for the endwise insertion of rail-ends, said easer-extensions 30 being longer than said fish-extensions at one end of said frog and said easer-extensions being shorter than said fish-extensions at the other end of said frog.

6. An integral frog comprising a throat, 35 a channel in advance of the throat, a fish-extension at each side of said channel, and an easer-extension at each side of said frog spaced laterally from said fish-extension at said side of said frog to form a rail-slot at each side of said frog, the walls of each of said rail-slots provided with tongues arranged to be received in the side-channels of rail-ends inserted endwise into said slots.

7. An integral frog comprising a throat, 45 a channel in advance of the throat, a fish-extension at each side of said channel, and an easer-extension at each side of said frog spaced laterally from said fish-extension at said side of said frog, said respective fish- 50 extensions and easer-extensions forming

mating extensions to form a rail-slot at each side of said frog, and said mating extensions having mating holes at the respective sides of the rail-slot therebetween for a rail fastening means.

55

8. An integral frog comprising a tongue, side-wings spaced from said tongue to form side-channels, easer-extensions connecting with said tongue, and fish-extensions at the sides of said easer-extensions to form rail-slots, said side channels having mouths the bottoms of which are formed by webs which connect with said side-wings and merge into said fish-extensions at points distanced from said tongue distances greater than the distances of the inner ends of said rail-slots from said tongue.

60

9. An integral frog comprising a tongue, side-wings spaced from said tongue to form side-channels, easer-extensions connecting 70 with said tongue, and fish-extensions at the sides of said easer-extensions to form rail-slots, said side-channels having mouths the bottoms of which are formed by webs which connect with said side-wings and merge into 75 said fish-extensions at points distanced from said tongue distances greater than the distances of the inner ends of said rail-slots from said tongue, and said easer-extensions and said fish-extensions provided with mating holes at the respective sides of said rail-slots for rail fastening means.

80

10. An integral frog comprising a tongue, a throat and an end-channel, easer-extensions at the heel of said frog beyond said 85 tongue, fish-extensions at the sides of said end-channel, fish-extensions at the sides of said easer-extensions to form rail-slots, and easer-extensions at the sides of said first-named fish-extensions to form rail-slots, the 90 side walls of all said rail-slots formed to conform to the side shapes of rails arranged to be received endwise into said rail-slots.

In testimony whereof, I have hereunto signed my name in the presence of two sub- 95 scribing witnesses.

ROBERT G. CRAWFORD.
